UNITED STATES PATENT OFFICE.

LEWIS WILLIAMS ALEXANDER, OF SAN ANTONIO, TEXAS.

DESIGN FOR A BOTTLE.

Application filed September 18, 1926. Serial No. 19,113. Term of patent 14 years.

To all whom it may concern:

Be it known that I, LEWIS W. ALEXANDER, a citizen of the United States of America, residing at San Antonio, in the county of Bexar and State of Texas, have invented a new, original, and ornamental Design for Bottles, of which the following is a specification, reference being had to the accompanying drawing, forming a part thereof.

In the drawings:

Fig. 2 is a side elevation of the bottle of the present invention.

I claim:

The ornamental design for a bottle, as shown.

LEWIS WILLIAMS ALEXANDER.
